UNITED STATES PATENT OFFICE.

FREDERIC E. BAGER, OF SOUTH MILWAUKEE, WISCONSIN, ASSIGNOR TO FREDERICK C. AUSTIN, OF CHICAGO, ILLINOIS.

BANK-SPUD FOR BARGES OR THE LIKE.

1,124,254.

Specification of Letters Patent. Patented Jan. 12, 1915.

Application filed February 13, 1911. Serial No. 608,404.

To all whom it may concern:

Be it known that I, FREDERIC E. BAGER, a citizen of the United States of America, and resident of South Milwaukee, Milwaukee county, Wisconsin, have invented a certain new and useful Improvement in Bank-Spuds for Barges or the like, of which the following is a specification.

My invention relates to what are known as spuds for barges or other boats.

It relates more particularly to the kind of spuds that are adapted to engage the banks of a stream or channel to hold the barge or other boat stationary. This is necessary, for example, in dredging, as in such case the barge or boat must be held firmly in a fixed position. Often this can only be done satisfactorily, when the stream or channel is narrow, by spuds that engage the banks. Prior to my invention the different arrangements for doing this were not always satisfactory. My invention contemplates, therefore, a barge or boat upon which the spuds are arranged horizontally, and in which mechanism is employed for operating the spuds either separately or simultaneously, each spud being provided, if desired, at its end with a movable shoe or plate that engages the sloping bank of the stream or channel, whereby the barge or boat is not only held stationary during the time that the dredge or excavator thereon is doing the required work, but is also maintained at a point midway between the two banks, without having the tops of the spuds interfere with the operation of the dredge or excavator, as will hereinafter more fully appear.

To these and other useful ends my invention consists in matters hereinafter set forth and claimed.

In the accompanying drawings, Figure 1 is a side elevation of a dredge or excavator barge provided with bank spuds, and means for operating the same, embodying the principles of my invention. Fig. 2 is a plan, on a smaller scale, of the barge or boat shown in Fig. 1. Fig. 3 is a cross-section on line 3—3 in Fig. 2.

As thus illustrated, the barge or boat A may be of any suitable or desired character. The excavator car or body B is mounted on a turn-table C disposed centrally of the deck of said barge or boat. At the center

of said turn-table there is located a vertically disposed shaft c which has its upper end 55 suitably connected with the engine D, whereby the shaft may be rotated at will. The said shaft is provided with sprocket wheels c' and c'', at the lower end thereof, and these are connected respectively by chains c''' and c'''' with the short vertical shafts a and a' which are located at opposite ends of the said barge or boat. These short shafts are provided with pinions a'' and a''' which engage the racks a'''' and a'''', the racks a'''' being 60 parallel and disposed at opposite sides of the pinion a'', and the racks a'''' being arranged in similar relation to the pinion a''', whereby all of said racks are disposed transversely of the boat or barge. Each rack is secured to 70 horizontally and transversely disposed spuds E, which latter are mounted to slide in the bearings e secured to the top of the deck of said barge or boat, each spud being provided at its outer end with a shoe or plate e' which 75 is pivoted at e'' to enable it to automatically adjust itself to the slope or angle of the bank. These spuds, therefore, are mounted horizontally upon the deck of the barge or boat, and are adapted to be moved in and 80 out by the sprocket chain transmission previously described.

From the foregoing it will be seen that I provide an improved bank spud arrangement which will not only hold the boat or 85 barge stationary while the excavator or dredge is performing the desired operation, but which will also maintain the said barge or boat at the center of the stream or channel in which it is operating, without in any 90 way mutilating or tearing up the banks thereof. The said spuds are easily controlled, regardless of the position of the excavator car or body on the turn-table, because the shaft from which the spuds are 95 controlled is located at the axis of said turn-table, whereby the position of the said housing or excavator body does not in any way affect the operativeness of the said transmitting connection by which the engine or 100 other motive power of the excavator is employed for forcing the spuds against the banks, and for then withdrawing them when it is necessary to move the excavator or 105 dredge to some other point in the stream or channel in which it is operating. As the

spuds operate horizontally, when thrust against the banks, they do not tend to lift the barge or boat out of the water. Also, as they have a long reach sidewise from the boat against the banks of the stream or channel, they give the excavator or dredge a greater degree of stability, and prevent it from tilting sidewise when the housing or body is swung around on the turn-table.

10 As they are horizontal, the tops of the spuds do not interfere with the operation of the dredge or excavator. For example, the spuds are always so entirely out of the way that they never interfere with the rotation 15 of the body B on the turntable.

What I claim as my invention is:—

1. In a barge or boat, bank spuds therefor, arranged horizontally upon the deck thereof at opposite sides of the boat, and 20 means for operating said spuds, the spuds at one side being opposed by those at the other side, and excavating apparatus movable freely around above said spuds.

2. In a barge or boat, bank spuds therefor, arranged horizontally upon the deck thereof, means for operating said spuds, said means comprising racks secured to the spuds, pinions engaging said racks, and 25 means below said deck for operating the pinions about vertical axes.

3. In a barge or boat, bank spuds therefor, arranged horizontally upon the deck thereof, means for operating said spuds, said means comprising pinions rotatable 35 about vertical axes, means for operating said pinions in unison, and parallel racks disposed at opposite sides of each pinion, whereby each pinion is engaged by two racks, each rack being secured to one of said 40 spuds.

4. In a barge or boat, bank spuds therefor, arranged horizontally upon the deck thereof, means for operating said spuds, said means comprising racks and pinions 45 for operating said spuds in unison, a centrally arranged shaft having suitable connection with said pinions, a turn-table having the said shaft located at the axis thereof, a body on said turn-table, and means on 50 said body for operating said shaft.

5. In a barge or boat, bank spuds therefor, arranged horizontally upon the deck thereof, means for operating said spuds endwise, said spuds being all arranged in 55 the same horizontal plane, and each spud being provided with a pivoted shoe or plate for engaging the banks of the stream or channel in which the barge or boat is floating, there being a plurality of said spuds at 60 each side of the boat, the spuds at one side being opposed by those at the other side, and excavating apparatus movable freely around above said spuds.

6. In a barge or boat, bank spuds therefor, arranged horizontally upon the deck

thereof, means for operating said spuds, said spuds being arranged in pairs at opposite ends of the barge or boat, the members of each pair being provided with a single operating device.

7. The combination of a barge or boat, spuds for said barge or boat disposed horizontally thereon, a movable member on said barge or boat, said member arranged to move over said spuds, mechanism on said 75 member for controlling said spuds, and a power transmitting connection between said spuds and mechanism, disposed in position not to interfere with or be injuriously affected by the movements of said member, 80 whereby said spuds are operable in any position of said body.

8. The combination of a barge or boat, horizontal spuds therefor, a movable body on the barge or boat, mechanism for operating said spuds horizontally in a plane below said body, and means on said body for controlling said mechanism.

9. A barge or boat, an excavator or dredge body movably mounted on said barge or boat, 90 and horizontal spuds between the bottom of said body and the deck of said barge or boat, projecting laterally therefrom, together with means on said body for controlling said spuds.

10. A barge or boat, an excavator or dredge body movably mounted on said barge or boat, and horizontal spuds between the bottom of said body and the deck of said barge or boat, projecting laterally therefrom, 100 together with means below the said deck for connecting and operating said spuds.

11. A barge or boat, an excavator or dredge body movably mounted on said barge or boat, and horizontal spuds between the bottom of said body and the deck of said barge or boat, projecting laterally therefrom, together with a source of power on said body, and means including a vertical shaft coincident with the axis of said body for connecting said shaft with said spuds.

12. A boat, a plurality of horizontal spuds on the deck thereof, and means below the deck for connecting said spuds together for simultaneous operation thereof.

13. A boat, horizontally disposed spuds thereon, projecting laterally at each side thereof, and an excavator or dredge body movably mounted on said boat, and means for projecting and withdrawing said spuds, the said disposition of said spuds in a horizontal plane permitting the said body to swing around without causing interference with said spuds.

14. A boat, a plurality of horizontal spuds on the deck thereof, a body movably carried on said boat, and means below the deck for connecting said spuds together for simultaneous operation thereof, together with

means on said body for controlling said spuds.

15. A boat, an excavator or dredge body movably mounted on said boat adapted to 5 turn around to operate at either side of the boat, spuds for the boat, mounted directly thereon, disposed in a plane below said body, and means on said body for operating said

spuds, operative in any position of said body.

Signed by me at Chicago, Cook county, Illinois, this 9th day of February, 1911.

FREDERIC E. BAGER.
